UNITED STATES PATENT OFFICE.

REES NICHOLS, OF PHILADELPHIA, PENNSYLVANIA, ASSIGNOR OF ONE-HALF TO
ARTHUR NICHOLS, OF PHILADELPHIA, PENNSYLVANIA.

WINDOW-CLEANER APPLIANCE.

Application filed March 9, 1927. Serial No. 173,990.

This invention relates to an improved window cleaner appliance, and an object of the invention is to provide, in a device of this character, a reciprocating member or rod and a casing therefor containing an electrical operating means operatively connected with the reciprocating member or rod for imparting movement to the latter, said reciprocating member or rod adapted to carry on its extremity an implement for cleaning a window, more especially show windows and the like.

Another purpose is to provide a plurality of implements, by which a window may be washed or mopped, wiped and finally polished, there being the provision of means on said implements common to them all for attaching them individually to the end of the reciprocating member or rod.

Still another purpose is to provide a polishing implement which includes a base with a rubber facing, against which a chamois skin or leather polisher engages, the polisher being transferable from one roller to another (which rollers are carried by the base of the implement) so as to change the polishing surface of the polisher when applying the finishing touches to the window.

A further purpose is to provide a handle for the casing (which carries the operating mechanism), said handle adapted to include several tubular connectors between the casing and the handle, the connectors being of different lengths, so as to provide handles of different lengths for the casing. For instance, in cleaning a large window a long handle would be necessary to reach the top of the window, and then as the cleaning process merges toward the bottom shorter handles are necessary.

A still further purpose is to provide means for holding the rollers carrying the polisher, to prevent the polisher from slipping, it being necessary, however, to operate the rollers manually in order to adjust the polisher from one to the other.

It is to be understood that the particulars herein given are in no way limitative, and that while still keeping within the scope of the invention, any desired modification of details and proportions may be made in the construction of the apparatus according to circumstances.

The invention comprising further features

and combination of parts to be hereinafter set forth, shown in the drawings and claimed.

In the drawings:

Figure 1—is a view in elevation of the improved window cleaning appliance constructed in accordance with the invention, showing the casing in section.

Figure 2—is a view in side elevation also showing the casing in section, and illustrating a connector for the handle and the casing, illustrating the bayonet slots and pin connections.

Figure 3—is an enlarged view in elevation showing the construction of the polishing implement and how it connects with the reciprocating member or rod.

Figure 4—is a sectional view on line 4—4 of Figure 3.

Figure 5—is a sectional view on line 5—5 of Figure 3.

Figure 6—is a view showing the manner of attaching the mop or brush to the end of the reciprocating member or rod.

Figure 7—is a view showing a wiper attached to the end of the reciprocating member or rod.

Referring to the drawings: 1 identifies a casing, in which is mounted an electric motor 2, the operating shaft 3 of which is mounted in suitable bearings 4 on the interior of the casing. This shaft 3 carries a pinion 5 meshing with a gear 6 having its shaft 7 mounted in bearings 8 on the interior of the casing. A suitable door 9 is hinged at 10 to the casing 1, and is provided for the purpose of permitting access to the interior of the casing for making any repairs to the electric motor or gears, or to a connecting rod or pitman 11. This pitman 11 is eccentrically connected or pivoted at 12 to the gear 6 and in turn pivotally connected at 13 to a rod 14, which operates through ball bearings 15 positioned within a tubular extension 16 of the casing 1. The exposed extremity of the reciprocating rod or member 14 carries either the mop, washer or scrubber, the wiper or the polishing implement.

The casing 1 has a tubular extension 17 at its other end, which interiorly carries wires 18 extending from the motor to a conventional type of switch 19, and the wires from the motor to an approved type of plug 20. These latter wires 21 as well as the wires 18 are encased in a suitable casing or insulator.

The tubular extension 17 operatively connects with a handle 22 by means of a tubular connector 23. The opposite ends of the connector 23 have bayonet slots 24 and 25, which engage with pins 26 and 27 of the handle 22 and the tubular extension 17.

The exposed end of the reciprocating member or rod terminates in a fork 28 the prongs of which have a transverse connecting bar 29 and also a transverse connecting tube 30. The tube 30 connects the extremities of the prongs, while the bar 29 connects the prongs adjacent where they merge into the rod 14.

Referring to Figure 3 in particular a holder 31 having a polishing member 32 is provided. This holder consists of a wooden base 33 which has a rubber facing 34, and secured to the base 33 are side plates 35. These side plates have ears 36 provided with openings 37 and 38, the openings 37 being in the central ears and the openings 38 being formed in the end ears. Suitable rollers with relatively large flanges are positioned between the end ears of the holder. The rollers 39 and 40 have their cores hollow, and connecting the rollers is a chamois skin or leather polishing member 41. This member 41 is adapted to be rolled from one roller to the other, in order to change its face which may contact with the window to be polished. Suitable leaf springs 42 are secured at 43 to the wooden base of the holder, and the extremities of the leaf springs bear against the face of the chamois skin or leather which is wound about the rollers, thereby acting to keep the rollers from turning, when the polisher is in action on the face of the window.

Secured to the side plates 35 are leaf springs 44 having knobs or plugs 45, which engage through the openings 37 and 38 of the ears 36. These knobs or plugs not only pass through the openings 37 and 38, but also extend telescopically into the tubular cores of the rollers and the tubular connecting rod 30. The knobs or plugs of the central springs 44 connect the holder to the prongs 28, while the plugs or knobs of the end leaf springs 44 extend into the cores of the rollers to journal the latter in position. Plates 46 are secured to the springs 44 and engage through slots 47 in the plates, and the lateral ends of the plates 46 act to limit the lateral movement of the leaf springs 44 by preventing them from being moved outwardly too far, when extricating the plugs or knobs from the the rollers or from the tubular rod 30.

As shown in Figures 6 and 7 there is a mop or scrubber and a wiper disclosed. Each of these is provided with ears 48, which engage exteriorly of the prongs 28 at their extremities, and carried by the ears are leaf springs 49 provided with plugs or knobs 50, which pass through openings 51 in the ears and into the tubular rod 30, for the purpose of connecting the mop, brush or scrubber, or the

wiper to the fork of the reciprocable rod or member 28.

A suitable device 52 is provided for holding the mop or scrubber, and the wiper at any desired angle, according to the position of the 70 casing which carries the operating mechanism for the rod.

In cleaning windows it is the purpose to first attach the mop, scrubber or similar device between the prongs 28, and after thoroughly washing the window, the scrubber or mop is removed and the wiper in Figure 7 substituted, the manner of attachment being the same as that with the mop or scrubber. After wiping the window it may be polished, 80 by removing the wiper and attaching the chamois skin holder, the attachment of this being accomplished in the same manner as the attachment of the wiper or the mop or scrubber. The casing 1 with its two tubular extensions 16 and 17 may be positioned at the desired angle, and by operating the button switch 19, the electric motor may impart movement to the gear 6, which will transmit its rotary movement to a reciprocating movement transmitted to the member or rod 14. It is possible to hold the handle of the casing 1, and by causing the motor to operate the rod or member 28 will reciprocate carrying the wiper or brush, or the polisher backwards 95 and forwards over the face of the window.

The invention having been set forth, what is claimed is:

1. A window cleaner, comprising a casing having a reciprocable rod therein and means for reciprocating the rod, a cleaning implement adapted to be actuated by said reciprocable rod, said reciprocable rod having a fork, and means carried by the implement and penetrating through the prongs of the fork 105 to attach the implement to the fork, said implement being capable of movement relative to the reciprocable rod.

2. A window cleaner comprising a casing and a reciprocable rod operable therein, said 110 rod having a fork and a tubular rod connecting the ends of the prongs of the fork, and a cleaning implement adapted to be actuated by said rod, and means carried by the implement for engaging through said prongs and 115 into the tubular rod to attach the implement in position.

3. In a window cleaner, the combination with a casing having a reciprocable rod with its exposed extremity terminating in a fork, 120 said fork having a rod connecting the prongs of said fork, an implement for attachment to the fork, means carried on the rod for attaching said implement to the fork of the reciprocable rod and adapted to be actuated by the 125 reciprocable rod, the implement adapted to have movement relative to the reciprocable rod.

4. In a window cleaner, the combination with a reciprocable rod having spaced prongs 130

projecting from one end, a tubular rod connecting their extremities, a holder for said rod and wherein the latter is operatively mounted, an implement adapted to be actuated by said rod, said implement comprising a base, tubular rollers mounted on the base, a pliable polishing member wound about the rollers and passing from one to the other and over the face of the base, and means carried by the base and operatively connecting with the tubular rod of the prongs for attaching the implement thereto.

5. In a window cleaner, the combination with a reciprocable rod having spaced prongs projecting from one end, a tubular rod connecting their extremities, a holder for said rod and wherein the latter is operatively mounted, an implement adapted to be actuated by said rod, said implement comprising 10 a base, tubular rollers mounted on the base, a pliable polishing member wound about the rollers and passing from one to the other and over the face of the base, and means carried by the base and operatively connecting with the tubular rod of the prongs for attaching the implement thereto, a casing for said rod and means in said casing for imparting movement to the rod, and a handle for the casing.

20 6. A window cleaner appliance including a cleaning implement, a reciprocable element having prongs and adapted to actuate said implement, a tubular rod connecting the extremities of the prongs, said implement having ears provided with leaf springs with means passing through the ears and engaging the tubular rod for attaching the implement to the element.

25 7. A window cleaner appliance including

a cleaning implement, a reciprocable element 40 having prongs and adapted to actuate said implement, a tubular rod connecting the extremities of the prongs, said implement having ears provided with leaf springs with means passing through the ears and engaging 45 the tubular rod for attaching the implement to the element, said implement carrying rollers and provided with additional ears, and additional leaf springs with means passing through the additional ears and engaging 50 into the rollers for operatively mounting the latter, and a pliable member passing over the face of the implement and adapted for action against a surface to be cleaned and connecting with said rollers.

55 8. In a window cleaner appliance including a cleaning implement, a reciprocable element having prongs and adapted to actuate said implement, a tubular rod connecting the extremities of the prongs, said implement 60 having ears provided with leaf springs with means passing through the ears and engaging the tubular rod for attaching the implement to the element, said implement carrying rollers and provided with additional ears, 65 and additional leaf springs with means passing through the additional ears and engaging into the rollers for operatively mounting the latter, and a pliable member passing over the 70 face of the implement and adapted for action against a surface to be cleaned and connecting with said rollers, and means for bearing against the pliable member where it connects with the rollers to prevent slipping thereof.

75 In testimony whereof he affixes his signature hereto.

REES NICHOLS.
